UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

DOOR-OPERATING MECHANISM FOR GONDOLA CARS.

No. 852,936.

Specification of Letters Patent.

Patented May 7, 1907.

Application filed April 3, 1905. Serial No. 263,412.

To all whom it may concern:

Be it known that I, ETHAN I. DODDS, a citizen of the United States, residing at Pullman, in the county of Cook and State of Illinois, have invented certain new and useful Improvements in Door-Operating Mechanisms for Gondola Cars, of which the following is a specification.

The object of my invention is to provide an improved door-operating mechanism for cars, particularly those of the gondola type. As is well known, these cars are provided with downwardly swinging hinged floor-sections or doors constituting unitedly the bottom of the car; and hitherto various devices have been proposed and employed for effecting the return of the doors to closed position after the discharge of the load wherein the doors are released and allowed to open under their own gravity and that of the load.

More particularly, my invention aims to provide a door-operating mechanism that is economical to construct, efficient in operation, and readily accessible for repair when it is in any way injured or broken. To this end my invention consists in a door-operating mechanism for cars of the type referred to having the peculiarities of construction and novel mode of operation substantially as hereinafter described and more particularly pointed out in the claims.

In the accompanying drawing I have shown so much of a steel gondola car as is essential to the disclosure and clear understanding of my invention; and referring thereto,—

Figure 1 is a cross-sectional view through a car-body equipped with my improved door-operating mechanism; Fig. 2 is a side elevational view of a portion of said car; Fig. 3 is a top plan view of one section of the floor; Fig. 4 is a side elevation of a portion of a car embodying my invention; Fig. 5 is a vertical section showing a part of the doors and their actuating mechanism; Fig. 6 is a side elevation of a portion of a car illustrating the embodiment of a modified form of my invention; Fig. 7 is a view similar to Fig. 5, but illustrating the modification shown in Fig. 6; and Fig. 8 is a partial cross section showing one of the cross-bearers in the car illustrated in Figs. 6 and 7.

Referring to the drawings, 1 designates spaced channel center sills, which, in cars of

this type, usually accommodate the draw- 55 bar and constitute the draft sills as well.

2 designates the side plates and 3 the end plates of the car-body, while the reference characters 4 are applied to transoms secured to and extending outwardly from the center 60 sills 1 flush with the side plates 2 of the car-body. These transoms, which may be made from an I-beam or a pair of channels, or any suitable pressed member, are characterized by the presence on their lower edges of laterally-extended flanges 5, which are vertically offset substantially midway of their length on a gradual curve, as shown at 5^a (Fig. 1).

6 designates each of a series of hinged doors or plates constituting those portions 70 of the floor of the car lying between the transoms 4; these doors, as herein shown, preferably consisting of pressed steel plates having depending flanges 6^a at the ends and along their outer edges. To operate these doors, 75 I provide at each side of the car, beneath each door, a rod 7 extending from one transom to the next, and on each end of these rods are mounted a pair of rollers 8 and 8^a, the edge of the downwardly turned flange of the 80 door resting upon the former, while the latter rolls on the flange 5, 5^a of the adjacent transom or cross-bearer. To each of the door-operating rods 7 is connected a bifurcated arm 9, to the outer end of which is piv- 85 otally connected a straight link 10, which, in turn, is connected by a short, curved link 11 and another straight link 12 to the outer end of an arm 13 that is fastened on a shaft 14 rotatably mounted in the projecting 90 flanges 15^a of a series of side stakes 15. Said shaft 14 may be provided at one end with a handle 16, or other suitable operating means.

In operation, when the door is open or dropped, the parts occupy the relative positions shown on the right hand side of Fig. 1. To close the door the shaft 14 is turned so as to swing the arm 13 upwardly slightly beyond vertical position above the shaft 14. This operation, through the described connections, draws the rollers 8^a outwardly and upwardly over the lower flanges of the transoms, and thereby, by means of rollers 8, raises the door 6 to horizontal or closed position, in which position the rollers 8^a, resting upon the elevated outer portions of the transom flanges support the door through the rod 7 and rollers 8, said mechanism being 105

automatically locked in the relative positions shown at the left in Fig. 1 through the engagement of the curved link 11 with the shaft 14. Conversely, to open the door it is necessary only to turn the shaft 14 in the opposite direction so as to throw the arm 13 outwardly and downwardly, which action forces the rollers 8 inwardly of the transoms, thereby allowing the door to drop as 10 said rollers descend the inclines 5^a.

In some cases it may be desirable to employ only a single rod or shaft instead of the number of rods 7 on one side of the car, and to accommodate such a shaft 7^a, as shown in Figs. 6, 7, and 8, I slot the intermediate cross-bearers or flying transoms 17 on an incline 17^a, at the same time providing the shaft with rollers 8 and 8^a, as in the construction described above. In cars of this type, 15 the operating shaft 14 may be connected to the shaft or rod 7^a at two or more places, as seems desirable. The operation of this modification will be clearly apparent from what has been set forth above.

20 This patent is intended to embrace only so much of the disclosure made herein as is covered by the following claims.

I claim:

1. A door operating mechanism for drop-bottom cars having a hinged floor section, 25 comprising tracks beneath the car body, a rod, rollers on said rod adapted to travel on said tracks, one or more other rollers on said rod engaging said hinged floor-section, operating means to move said rod and rollers toward and from the hinges of said floor-section whereby to lower and raise said floor-section, substantially as described.

2. A door operating mechanism for drop-bottom cars having a floor-section hinged longitudinally of the car, comprising transverse tracks beneath the car body, a rod, rollers on said rod adapted to travel on said tracks, one or more other rollers on said rod 30 engaging said hinged floor-section, and operating means to move said rod and rollers inwardly and outwardly relative to the sides of the car and thereby lower and raise said hinged floor-section, substantially as described.

3. In a door operating mechanism for drop-bottom cars having a hinged floor-section, comprising inclined transverse tracks beneath the car body, a rod, rollers on said 35 rod adapted to travel on said tracks, other rollers on said rod engaging the hinged floor-section, and means to move said rod and rollers inwardly and outwardly relative to the sides of the car whereby to lower and raise said floor-section, substantially as described.

4. A door operating mechanism for a drop-bottom car having a hinged floor-section,

comprising transoms with integral flanges, a rod, rollers on said rod adapted to travel on the flanges of said transoms, other rollers on 65 said rod engaging said hinged floor-section, and operating means to move said rod and rollers inwardly and outwardly relative to the sides of the car thereby lowering and raising said floor-section, substantially as described. 70

5. A door operating mechanism for a drop-bottom car having a hinged floor-section, comprising transoms with inclined integral flanges, a rod, rollers on said rod adapted to travel on the flanges of said transoms, other rollers on said rod engaging said hinged floor-section, and operating means to move said rod and rollers inwardly and outwardly relative to the sides of the car thereby lowering and raising said floor-section, substantially as described. 75

6. A door operating mechanism for a drop-bottom car having a hinged floor-section, comprising transoms having flanges, a rod, rollers on said rod adapted to travel on the 80 flanges of said transoms, other rollers on said rod engaging said hinged floor-section, an operating shaft mounted adjacent to the side wall of the car, and means connecting said operating shaft with said rod including an 85 arm on said shaft and one or more links, substantially as described. 90

7. In a railway dumping car, the combination of a car-body having a hinged floor-section, side posts or stakes provided with projecting flanges or legs, an operating shaft rotatably mounted in said flanges or legs, transoms having inclined flanges, a rod, rollers on said rod adapted to travel on said flanges, other rollers on said rod engaging said hinged 95 floor-section, and means connecting said operating shaft and rod including an arm secured to said shaft and one or more links, substantially as described. 100

8. In a railway dumping car, the combination of a metallic car-body having a hinged floor-section, side posts or stakes provided with projecting flanges or legs, an operating shaft rotatably mounted in said flanges or legs, transoms having inclined flanges, a rod, rollers on said rod mounted to travel on said transom flanges, other rollers on said rod engaging said hinged floor-section, an arm secured to said operating shaft, and one or more links connecting said arm with said rod, one of said links being curved and adapted to hook over said operating shaft to retain said floor-section in closed position, substantially as described. 105
